UNITED STATES PATENT OFFICE.

JOHANN PAPIEZ, OF BERLIN, GERMANY.

FLYING MACHINE.

1,407,437.

Specification of Letters Patent. Patented Feb. 21, 1922.

Application filed September 24, 1920. Serial No. 412,610.

To all whom it may concern:

Be it known that I, JOHANN PAPIEZ, a citizen of the German Republic, residing at 1 Landsbergerplatz, Berlin, Germany, have 5 invented certain new and useful Improvements in Flying Machines, (for which I have filed applications in Germany on August 2nd, 1919, and July 10th, 1920,) of which the following is a specification.

10 This invention relates to improvements in flying machines and more particularly to flying machines with a lifting propeller. The flying machine according to the invention comprises a number of arrangements 15 which greatly facilitate and improve the practical application of such machines. These arrangements affect the lifting propeller itself and its drive on the one hand, and on the other hand they have to do with 20 the members for moving the machine forward and for steering the same, and with the cushioning members for preventing serious jolts or shocks when the machine returns to the ground.

25 In the accompanying drawing, which discloses the parts of a flying machine to which the invention refers,

Fig. 1 is a side view, partly in longitudinal section,

30 Fig. 2 is a plan view with the lifting propeller omitted, and

Fig. 3 is a detail.

The plan view of the frame 1 of the flying machine with the bottom 2 and the top 35 stays 3 is circular in shape. The entire body of the machine rests upon feet 5. These are guided in air cylinders 6 which have small air passages 7 at their upper ends, so that when the machine alights upon 40 the ground and the feet are caused to enter the cylinders, the air in the latter is compressed and partly or gradually escapes through the openings 7. When the machine rises again, the air returns into the cylinders 45 through the openings 7, and the feet drop or move out again of their own weight. To ensure uniform movements of the feet they may be connected to each other by suitable stays.

50 The lifting propeller 18, and a propeller 11 mounted on the shaft 12 and operating to drive the flying machine forward in the direction indicated by the arrow, are rotated by a motor in the gear box 15. The 55 propeller 11 is mounted at a considerable distance from the frame of the flying ma-

chine, the said distance being about equal to the diameter of the propeller. The lifting propeller 18 is mounted on a vertical shaft at a considerable height above the top 60 of the flying machine. The whole length of the shaft 16 from the frame to the propeller is surrounded by a hollow column 17 which forms an extension of the roof 14. By the large air space thus provided between the body of the machine and the propeller the air is enabled to pass without hindrance to the wings of the propeller and their efficiency is thus improved. The efficiency of the advancing propeller 11 is also 70 enhanced in a similar manner by its horizontal distance from the body of the machine.

Arranged at both sides of the advancing propeller 11 are steering propellers 8 and 9 75 which are driven from the shaft 12 of the advancing propeller 11 in the manner described below.

Pulled by springs 21 into a wedge-shaped groove 20 (Fig. 3) in the shaft 16 of the 80 lifting propeller 18 is a brake block 19. The brake block 19 is mounted on a two-armed lever 22 to whose longer arm a wire 23 (Fig. 1) is attached. This wire is adapted to be wound onto a roll 24 which is 85 turned by a crank 25 with the aid of a worm or screw gear. By rotating the crank the lever 22 may be shifted and the brake block thus lifted more or less clear of the shaft 16 in opposition to the springs 21. By this 90 means the propeller may be regulated so as to revolve at any desired speed, this being particularly important for the gentle alighting of the flying machine.

The shafts 26 and 27 of the steering propellers 8 and 9 are mounted upon sliding members 28, 29, and are generally driven with the aid of belts or other transmitting members 30, 31 from the shaft 12 of the advancing propeller 11 which is rotated by the 95 motor. The sliding members 28, 29 which glide in suitable slideways are drawn apart by adjustable spring tensioning devices 32, 33 so that the driving bands or belts 30, 31 are generally taut. The sliding members 100 are each connected to a draw wire 34, 35 which pass over suitable guide rolls 36 to driving rolls 37 each of which is adapted to be rotated by a crank handle 38, 39 with the aid of a screw gear. The driving belts 110 can thus be slackened so as to put the steering propellers entirely or partly out of op-

- eration. The crank handles 38, 39 are situated like the crank 25 for regulating the speed of the lifting propeller so as to be within convenient reach of the pilot.
- 5 I do not desire to limit myself to the exact construction shown and described, as it is evident that other means along the same lines may be utilized to secure quite the same results.
- 10 I claim:
1. In a flying machine; a long vertical shaft with a lifting propeller greater in diameter than the base of the machine and mounted at a considerable distance above the body of the machine; a long horizontal shaft; an advancing propeller mounted on the horizontal shaft at a considerable distance from the body of the machine; steering propellers arranged symmetrically at both sides of the advancing propeller, sliding supports, shafts for the steering propellers mounted in the said supports; driving bands for driving the steering propeller shafts from the advancing propeller shaft; adjustable springs attached to the said supports and adapted to normally tauten the said bands; crank handles for shifting the said supports in opposition to the said adjustable springs, and links between the crank handles and the said supports, substantially as described.
  - 15 2. In a flying machine; a long vertical shaft with a lifting propeller greater in diameter than the base of the machine and mounted at a considerable distance above the body of the machine; a long horizontal shaft; an advancing propeller mounted on the horizontal shaft at a considerable distance from the body of the machine; a brake for regulating the speed of the lifting propeller; springs normally pressing the brake against the lifting propeller shaft; a lever for actuating the said brake; a crank handle within easy reach of the pilot for working the said lever; steering propellers arranged symmetrically at both sides of the advancing propeller, sliding supports; shafts for the steering propellers mounted in the said supports; driving bands for driving the steering propeller shafts from the advancing propeller shaft; adjustable springs attached to the said supports and adapted to normally tauten the said bands; crank handles for shifting the said supports in opposition to the said adjustable springs, and links between the crank handles and the said supports, substantially as described.
  - 20 3. In a flying machine; a long vertical shaft with a lifting propeller greater in diameter than the base of the machine and mounted at a considerable distance above the body of the machine; a long horizontal shaft; an advancing propeller mounted on the horizontal shaft at a considerable distance from the body of the machine; a brake for regulating the speed of the lifting propeller; springs normally pressing the brake against the lifting propeller shaft; a lever for actuating the said brake; a crank handle within easy reach of the pilot for working the said lever; steering propellers arranged symmetrically at both sides of the advancing propeller, sliding supports; shafts for the steering propellers mounted in the said supports; driving bands for driving the steering propeller shafts from the advancing propeller shaft; adjustable springs attached to the said supports and adapted to normally tauten the said bands; crank handles for shifting the said supports in opposition to the said adjustable springs, and links between the crank handles and the said supports, substantially as described.
  - 25 4. In a flying machine; a long vertical shaft with a lifting propeller greater in diameter than the base of the machine and mounted at a considerable distance above the body of the machine; a long horizontal shaft; an advancing propeller mounted on the horizontal shaft at a considerable distance from the body of the machine, a brake for regulating the speed of the lifting propeller, steering propellers arranged symmetrically at both sides of the advancing propeller; sliding supports; shafts for the

In testimony whereof I have signed this 80
specification in the presence of two wit-
nesses.
